UNITED STATES PATENT OFFICE

2,586,548

SHUTTLE WINDER

John E. McArthur, Dauphin, Manitoba, Canada

Application September 29, 1949, Serial No. 118,584

4 Claims. (Cl. 242—52)

1

My invention relates to new and useful improvements in shuttle or needle winders for use in winding the needles used in "hanging" or "seaming on" fishing gill net mesh to the side lines thereof, an object of my invention being to provide a device of the character herewithin described which facilitates the winding on of the stranded material or twine upon the special form of needle or shuttle conventionally used.

A further object of my invention is to provide a device of the character herewithin described, the use of which provides a more uniform winding of the thread upon the needle.

Another object of my invention is to provide a device of the character herewithin described, which is readily adaptable to be driven by mechanical or electrical means.

A yet further object of my invention is to provide a device of the character herewithin described whereby fishing needles or shuttles may be wound substantially faster and more accurately than by hand.

A still further object of my invention is to provide a device of the character herewithin described which is relatively economical in manufacture, sturdy in construction, and otherwise well suited for the purpose for which it is designed.

With the foregoing objects in view, and such other objects and advantages as will become apparent to those skilled in the art to which this invention relates as this specification proceeds, my invention consists essentially in the arrangement and construction of parts all as hereinafter more particularly described, reference being had to the accompanying drawings in which:

Figure 1 is a side elevation of my device.

Figure 2 is a top plan view of my device.

Figure 3 is a fragmentary end elevation of my device taken substantially along the lines 3—3 40 of Figure 1.

Figure 4 is a fragmentary side elevation of one end of my device opposite to that of Figure 1.

Figure 5 is a perspective exploded fragmentary detail of the spindle and traveller mechanism.

Figure 6 is an enlarged perspective view of a conventional shuttle or needle.

Figure 7 is a cycle of operations diagram predicated upon one revolution of the driving wheel.

In the drawings like characters of reference indicate corresponding parts in the different figures.

The special needle or shuttle used in the seaming of gill nets to the float and sinker side lines facilitates this seaming as well as providing hand

2

means for manipulating the bulk of seaming twine or cord through the mesh apertures. The design of the needle shown in Figure 6 of the accompanying drawings permits same to be passed readily through the mesh apertures and, the special method of winding the twine upon the needle before seaming, permits same to be disengaged therefrom by a slight jerk but at the same time allows the needle to depend or hang from the net being worked upon without unwinding of the remaining cord, an advantage extremely important in the rapid and accurate seaming of nets to lines.

The winder hereinafter to be described rapidly transfers the seaming twine from a spool on to the shuttle or needle with the desired lay and at the same time maintains an even tension thereby facilitating the seaming operation.

Proceeding now to describe my invention in detail, it will be seen upon reference to the accompanying drawings that I have illustrated in Figure 6 a conventional fisherman's needle or shuttle which includes a pair of elongated open-sided flanks 1 spanned by an interiorly spaced winding core 2 having a resilient tongue 3 projecting therefrom and in the same plane as the aforementioned flanks 1, clearance 4 being provided therearound. The flanks 1 are spaced at what I define as the unsupported end 5 of the needle to provide an entrance opening 6 for the winding upon the core of stranded material in the form of seaming twine 7. The reference to the unsupported end 5 will become apparent when the structure of the device is recited hereinafter.

The stranded material or twine 7 is normally placed upon the needle by hand passing under the tongue 3, down towards the unsupported end 5 of the needle, around the entrance opening 6, along the opposite side of the winding core 2, and thence around the tongue 3. In this connection it will be apparent that the tongue 3 is capable of deflection to one side of the plane of the flanks 1 in order to facilitate the engagement therearound of the seaming twine 7. This deflection is indicated in phantom by the reference character 8.

The device for winding the twine 7 upon the needle is mounted upon a substantially rectangular base panel 9 which in turn carries vertical supporting structure 10 adjacent one end 11 thereof in the form of an upstanding post 11' braced by the diagonal 12. A drive wheel 13 is journaled for rotation toward the upper end 14 of the post 11', a handle 15 being secured to the drive wheel spindle 16 which extends through the

post 11' for the purpose of rotating said drive wheel.

A conventional stranded material carrying spool 17 is supported for rotation around the longitudinal axis thereof within a spool holder 18 which includes a pair of end plates 19 and a rear support strip 20. The rear support strip 20 is attached to the drive wheel 13 and is rotatable therewith, by means of a ring 21 concentric with drive wheel 13 and bolted or otherwise secured to one of the spokes 22 thereof by a connecting rod pin 23.

A connecting rod 24 is journalled for rotation upon pin 23 and it should be noted that the end 25 of the connecting rod which is secured to the wheel 13 is situated between said wheel and the aforementioned ring 21 thereby permitting free rotation of the end 25 of the rod 24, the purpose of which will hereinafter be described.

The needle or shuttle upon which the stranded material 7 is to be wound is detachably secured within a chuck 26 extending from and secured to the end 27 of a spindle 28 which in turn is mounted for rotation between vertical supports 29 and 30 secured to the aforementioned base 9. This chuck comprises a pair of semi-tubular, elongated jaws 31 curved to complement the flanks 1 of the needle and having inherent resiliency towards one another so that same may be spread apart by the insertion of the needle yet which will grip same firmly when in position. A relatively short spring strip 32 is secured to the base 33 of the chuck and is provided with a lip 34 which engages with the interior surface 35 adjacent the nose 36 of the needle and anchors same securely within the chuck 26. It will be observed upon reference to Figure 2 of the accompanying drawings that the aforementioned spindle 28 together with the chuck 26 is disposed upon one side of the plane on which the drive wheel 13 lies and normal to the rotary axis thereof.

I have provided a stranded material distributor collectively designated 37 which conveys the twine 7 from the spool 17 to the needle 1' within the chuck 26 which includes a tube or guideway 38 secured to the aforementioned ring 21 and extending towards the rim 39 of the drive wheel 13. The tube 38 curves towards the chuck 26 and is supported by means of a curved strip 40 also secured to the ring 21 which strip also carries a twine tensioner 41 comprising a pair of discs spring-tensioned together between which the twine 7 passes thereby preventing backlash.

From the foregoing and upon reference to Figure 3 of the accompanying drawings, it will be apparent that the distributor 37 rotates with the drive wheel 13 and projects therefrom. It is so positioned to move through a planar course parallel to and to one side of the longitudinal axis of the spindle 28 and the chuck 26.

In order to place the twine 7 upon the needle 1' in the manner hereinbefore described, it is necessary to deflect the tongue 3 to one side of the plane of the flanks 1, pass the thread between the tongue and the flanks, then down towards the entrance opening 6 whereupon the needle has to be rotated through 90° in order that the thread or twine can be passed up the other side of the winding core 2 whereupon the tongue 3 is deflected again in order to repeat the operation. The position of the discharge end 42 of the distributor 37 therefore assumes importance inasmuch as this end rotates in its own plane parallel to and with the drive wheel 13. This

discharge end which takes the form of an aperture within the extremity of the supporting strip 40 is positioned so that the area enclosed by the course thereof is nearer to the plane of the flanks 1 of the needle when same are parallel to this enclosed area than the tip 43 of the tongue 3 when same is depressed so that the twine 7 is passed between said tip and said flanks. Upon reference to Figure 3, the foregoing will be apparent, as in this view the broken line 44 represents the plane through which the drive wheel 13 rotates and broken line 45 indicates the planar course of the discharge end 42 of the distributor 37.

In order to obtain the correct positioning of the shuttle or needle it is necessary that it is revolved through 180° for each complete revolution of the drive wheel 13. This is because, in effect, and due to the positioning of the spool 17 and the distributor 37, the thread is passed backwards and forwards along the length of the needle during one revolution of the drive wheel. The rotation of the shuttle or needle 1' within the chuck 26 is effected by the rotation of the spindle 28 and actuated by the aforementioned connecting rod 24. The opposite end 46 of the connecting rod 24 to that which is attached to the drive wheel 13, is pivotally secured to a slide-box 47 which comprises a casing containing a pair of rollers 48 which engage with a rail 49 extending between the aforementioned supporting posts 29 and 30 subjacent to and slightly to one side of the aforementioned spindle 28. This slide-box in conjunction with what I define as a traveller collectively designated 50 reciprocates longitudinally upon the rail 49 under the influence of the rotation of the drive wheel 13.

The traveller 50 comprises a bar 51 secured to the slide-box 47 and upstanding therefrom, the upper end of said bar being curved or angulated as at 52 to engage a sleeve 53 which surrounds the aforementioned spindle 28. Sleeve 53 includes a cylindrical portion 54 and a pair of end caps 55 integral therewith, the portion 52 of bar 51 being situated between the end caps and transferring the longitudinal motion of the slide-box to the longitudinal motion of the sleeve. The sleeve 53 is drilled longitudinally to slidably engage spindle 28 and is provided with a pin or follower 56, the end of which extends inwardly to protrude within the longitudinal drilling thereof. The extremity of pin 56 which extends through hole 59 and engages with a cam track in the form of an elongated spiral guide 57 formed along the length of spindle 28 between, and on that portion thereof, posts 29 and 30.

Sleeve 53 is provided with a pair of ratchet cams 58 and 59 engageable by a spring strip 60 secured to the slide-box 47 which permits the sleeve to be rotated clockwise with relation to Figure 3. The engagement of pin 56 within the spiral guide 57 (which is formed counter-clockwise upon spindle 28 when viewed from the left-hand end of Figure 1) will cause the sleeve 53 to rotate in the same direction when the slide-box 47 moves along the rail 49 in the direction of arrow 61 under the influence of the connecting rod 24 driven by the wheel 13. Consequently, no rotation of spindle 28 or chuck 26 will occur.

Rotation of shaft 28 is further prevented during this movement by the provision of a double ratchet cam collar 62 having projections 63 upon the circumference thereof, and which is secured to one end of shaft 28 adjacent post 29. The projections 63 are engageable by a resilient spring

lever or tongue 64 secured to post 29 and prevent rotation of the shaft in a clockwise direction when viewed from the left-hand end of Figure 1.

However, when the slide-box 47 moves in the opposite direction to the arrow 61, the ratchet cam 59 engages with the extremity of strip 60 and prevents the sleeve 53 from rotating. But due to engagement of pin 56 within spiral guide 57, spindle 28 is rotated through 180° thereby rotating the chuck 26 and the needle 1' through the same number of degrees.

When the needle is in the position shown in the drawings, the resilient tongue 3 thereof is deflected towards the plane of the drive wheel 13 for the purpose hereinbefore described by the provision of a cam 65 which, in this embodiment, is provided on the rim 39 of the drive wheel 13 and rotates therewith. A reciprocating beam 66, supported by angulated bracket 67, is situated at right angles to the rotary plane of the cam 65 being pivoted upon a pin 68 and overspanning the aforementioned chuck 26 and shuttle 1'. A cam follower 69 in the form of a wheel is mounted for rotation within one end 70 of the beam 66 and engages the cam 65 together with the rim 39 of the wheel 13.

The reciprocating beam 66 extends over the shuttle 1' and downwardly theretowards and is provided upon the end 71 thereof which is on the opposite side of the shuttle to that of the distributor 37, with an intermittently tongue-contacting pusher 72 which deflects the tongue to one side towards the plane of the drive wheel 13 once each revolution of said wheel. In order to maintain the follower 69 within contact with the rim 39, a tension spring 73 is provided which, in this embodiment, extends between the end 71 of the reciprocating beam 66 and an offstanding bracket 74 secured to post 30.

Having therefore described my device in detail, its method and sequence of operation will now be presented. It is to be understood that, during one revolution of the drive wheel 13, stranded material or twine 7 is passed along one side of the needle 1', whereupon the needle is rotated through 180°, the twine at this point passing into the entrance opening 6 of the needle and then back along the other side of the needle to be passed between the now deflected tongue 3 and the flanks 1 of the needle. Reference to the sequence diagram shown in Figure 7 will show that the outer circle 75 thereof represents 360° of the drive wheel 13, rotating in a clockwise direction. During approximately 150° of this revolution, the twine 7 is being passed down the side of the needle adjacent the drive wheel 13 due to the location of the discharge end 42 of the distributor 37. Coincidentally with this movement, the aforementioned slide box 47 and traveller 50 are moving along the rail 49 in the direction of arrow 61, the sleeve 54 rotating upon spindle 28 due to the engagement of pin 56 with spiral guide 57, rotation of spindle 28 being prevented by the aforementioned projections 63 upon the collar 62.

At this point the slide box 47 and traveller 50 reach the end of rail 49 and commence travelling in an opposite direction to arrow 61 at which time the strip 60 engages with the ratchet 59 and prevents the sleeve rotating thereby forcing the spindle 28 to rotate through 180° together with the chuck 26 and the shuttle or needle 1'. The idling portion of the slide-box 47 and traveller 50 is indicated by the dotted line 76 whereas the rotation of spindle 28 is indicated by the full line 77 between the arrows 78.

During the rotation of spindle 28 the twine is being passed along the opposite side of the needle 1' which is now being brought to face the drive wheel 13, same reaching the resilient tongue 3 at the completion of approximately 330° of revolution of the drive wheel 13. At this point the cam follower 69 commences to engage the cam 65 upon the rim 39 of the wheel 13 thereby actuating the reciprocating beam 66 in the direction of arrow 79. This causes the depresser 72 to move the tongue 3 of the needle 1' towards the plane of the drive wheel 13 and, due to the aforementioned positioning of the discharge end 42 of the distributor 37 secured to the drive wheel, the twine 7 is passed between said tongue and the flanks 1 of the needle thereby engaging same. In the foregoing recitation it is to be assumed that the drive wheel is being rotated by means of handle 15 in a clockwise direction with reference to Figure 1. The radial movement of the drive wheel 13 during the depressing and releasing of the tongue 3 is indicated by the quadrant 80 in Figure 7.

From the foregoing it will be appreciated that continuous winding of twine 7 upon the needle takes place, the needle rotating through 90° between the stage at which the tongue 3 is depressed and the stage at which the twine reaches the open end thereof at which point rotation of the needle through a further 90° occurs thus completing half a cycle.

Since various modifications can be made in my invention as hereinabove described, and many apparently widely different embodiments of same made within the spirit and scope of the claims without departing from such spirit and scope, it is intended that all matter contained in the accompanying specification shall be interpreted as illustrative and not in a limiting sense.

40. What I claim as my invention is:

1. A shuttle winder comprising in combination with a shuttle having a pair of elongated, open-sided flanks spanned by an internally spaced winding core and a resilient tongue projecting from said core in the plane of said flanks, and a spool from which stranded material is wound on to said shuttle, a supporting structure, a drive wheel thereon, a spindle disposed on one side of the plane on which said wheel lies normal to the rotary axis thereof, chuck means on the end of said spindle for carrying said shuttle rotatably about the longitudinal axis thereof, means for rotating said spindle, said means comprising an elongated spiral guide extending around the surface of said spindle, a connecting rod on said drive wheel, and a traveller on the end of said connecting rod opposite to that connected to said drive wheel, said traveller engaging said guide so as to rotate said spindle upon movement of said connecting rod under the influence of said drive wheel, means for deflecting said shuttle tongue to one side of the plane of said flanks towards said drive wheel once every half revolution of said shuttle, and a stranded material distributor on said drive wheel, rotatable therewith and projecting therefrom to an extent such that it moves through a planar course the area enclosed whereby is nearer to the plane of said shuttle-flanks when parallel to said enclosed area, than the tip 75 of said tongue when deflected as aforesaid, so that said distributor passes said stranded material between said tip and the plane of said flanks, said spindle rotating said shuttle 90° between the stage at which said tongue is deflected and the subsequent stage at which said distributor de-

livers said material to the unsupported end of said shuttle, at which end the said flanks thereof are spaced to provide an entrance opening for said stranded material to said winding core.

2. A shuttle winder comprising in combination with a shuttle having a pair of elongated, open-sided flanks spanned by an internally spaced winding core and a resilient tongue projecting from said core in the plane of said flanks, and a spool from which stranded material is wound on to said shuttle, a supporting structure, a drive wheel thereon, a spindle disposed on one side of the plane on which said wheel lies normal to the rotary axis thereof, chuck means on the end of said spindle for carrying said shuttle rotatably about the longitudinal axis thereof, means for rotating said spindle, means for deflecting said shuttle tongue to one side of the plane of said flanks towards said drive wheel once every half revolution of said shuttle, said means comprising a cam secured to said drive wheel and rotating therewith, a reciprocating-beam at right angles to the rotary plane of said cam and overspanning said shuttle, a follower secured to said beam and engaging said cam for effecting said reciprocation, and an intermittently tongue-contacting pusher on the end of said beam and on the opposite side of said shuttle to that of said distributor for deflecting said tongue, and a stranded material distributor on said drive wheel, rotatable therewith and projecting therefrom to an extent such that it moves through a planar course the area enclosed whereby is nearer to the plane of said shuttle flanks when parallel to said enclosed area, than the tip of said tongue when deflected as aforesaid, so that said distributor

passes said stranded material between said tip and the plane of said flanks, said spindle rotating said shuttle 90° between the stage at which said tongue is deflected and the subsequent stage at which said distributor delivers said material to the unsupported end of said shuttle, at which end the said flanks thereof are spaced to provide an entrance opening for said stranded material to said winding core.

10 3. The device according to claim 1 in which said spool is mounted upon said drive wheel for rotation therewith.

4. The device according to claim 2 in which said spool is mounted on said drive wheel for rotation therewith, and in which said means for rotating said spindle comprises an elongated spiral guide extending around the surface of said spindle, a connecting rod on said drive wheel, a traveller on one end of said connecting rod opposite to that connected to said drive wheel, said traveller engaging said guide so as to rotate said spindle upon movement of said connecting rod under the influence of said drive wheel.
